DESIGN FOR A COIN BANK

Louise B. Johnstone, Grosse Pointe, Mich.

Application September 30, 1940, Serial No. 95,531

Term of patent 7 years

To all whom it may concern:

Be it known that I, Louise B. Johnstone, a citizen of the United States of America, residing at Grosse Pointe, in the county of Wayne and State of Michigan, have invented a certain new, original, and ornamental Design for a Coin Bank, of which the following is a specification, reference being had therein to the accompanying drawing, forming a part thereof in which:

I claim:

The ornamental design for a coin bank, substantially as shown.

LOUISE B. JOHNSTONE.
